CALCULATING MACHINE

Carl E. Lenz, Jamaica, N. Y., assignor to Remington Rand Inc., Buffalo, N. Y., a corporation of Delaware

Application June 16, 1939, Serial No. 279,384

2 Claims. (Cl. 235—61.6)

This invention relates, generally, to calculating machines, and more particularly to a perforated card machine adapted to perform the operation of addition, subtraction, and multiplication. Such a machine is described in application S. N. 69,570 of Elmer H. Dreher, filed March 18, 1936, and in the British Patent No. 490,418, issued March 18, 1936.

The machine embodying this invention comprises three principal mechanisms for the performance of three distinct operations. The mechanisms and their functions are namely, (1) a multiplying mechanism, which multiplies a plurality of digits, (set therein either manually or by a perforated record card) to obtain a product which, together with the factors, is printed on a record sheet and is also run into an accumulator from which totals may be obtained; (2) a sensing mechanism which sensed the factors from a perforated card, and causes a corresponding set-up in the multiplying mechanism; and (3) a punching mechanism which, under control of the multiplying mechanism, punches factors, products, and totals in a record card. In short, the machine is adapted to sense factors from a perforated card, and compute the product which is then punched in the same card, printed on a record strip, and stored in a totalizer. The totals may be printed on the record strip or punched in a separate summary card.

Each of the three mechanisms is suitably interconnected by appropriate control devices.

The machine is of a character wherein the multiplier or multiplicand, or both, may be set into the multiplying mechanism either manually or under control of a perforated card. Also, the multiplier may be set up by manual operation and the multiplicand by a perforated card, and vice versa. Further, a multiplier, once set in the multiplying mechanism, may be retained therein, for successive cycles of the machine by simply depressing a repeat control-key. Thus it is possible to set up a "master" or common multiplier and then send a card, having only a multiplicand punched therein, through the sensing unit, whereupon, the multiplicand contained in the card will be set into the multiplying mechanism. The timing of the various mechanisms is so co-related that as the card is sensed and the set-up is made, a control link is depressed to set the multiplying mechanism in operation.

While the multiplying unit is going through its computing cycle, the card is passed from the sensing chamber into a punch-unit wherein it is re-

tained until the multiplication operation of the multiplying unit is completed, and, the product, together with the multiplier, is punched in the card.

Upon completion of each multiplying cycle, the multiplicand is cleared from the machine, but the multiplier remains set up in the mechanism until the clear key is operated by the operator or the mechanism is cleared by the use of a "clear" control card.

In previous machines, a complete cycle would take place each time a card was sensed. That is to say, for example, when a master card, the sole purpose of which was to set up a multiplier in the machine, was sensed, the multiply-control link would be tripped and the multiplying mechanism would go through a cycle although no multiplication would be performed. Next, when a detail card, containing the multiplicand, was sensed, the multiplying mechanism would, again, be set in operation, at which time the mechanism would perform a multiplication, and would thus effect the various other operations assigned to the multiplying unit. When next a clear card was sensed, the multiplying mechanism would again be set in operation and would again go through a cycle without performing any multiplications.

It is apparent, therefore, that, under such conditions, should there be a repeated series of cards comprised of a "master" card, a "detail" card, and a "clear" card, the multiplying mechanism would, in each case, go through three complete cycles for every multiplication performed. This means that two of the three cycles of the multiplying unit, in so far as actual effective computation was concerned, were unnecessary and, therefore, wasted.

The machine of this invention, however, provides a means whereby a "master" card, or a "clear" card, may be sensed; the multiplier "set-up" either made or cleared (depending on the card); and the card ejected; without the multiplying mechanism going through a cycle.

This arrangement effects a considerable saving of time, for the card feeding and sensing mechanism operates at a speed five times as great as that of the multiplying mechanism. It is apparent, therefore, that only one fifth the time required to sense the card and retain it in the punch unit until the multiplying mechanism completes a cycle before ejecting the card, will be necessary when the card is simply sensed and ejected immediately.

Another advantage of the present machine, over

previous ones, is that since the head, or multiplying mechanism, does not go through a cycle, the listing mechanism will not be operated on the "multiplier set-up" and "clear" card sensing. Thus there will not be a blank space on the record strip, such as would appear on the old machines, for each of the non-multiplying cycles. Hence a more readily legible record results, a saving of paper is effected, and unnecessary wear and tear on the multiplying unit is avoided.

It is, therefore, the principal object of this invention to provide a card controlled multiplying machine which will not go through a multiplying cycle when a "master set-up" card or a "clear" card is sensed.

A second object of this invention is to provide a card controlled multiplying machine which will permit the sensing of a greater number of cards, in a given time, than was previously possible.

Another object of this invention is to provide a card controlled multiplying machine in which a control mechanism, operated through a control hole in the card, will cause the card to be ejected from the machine without the multiplying mechanism going through a cycle.

Other objects and structural details of the invention will be apparent from the following description when read in conjunction with the accompanying drawings, wherein:

Fig. 1 is a left-hand elevational view of the calculating machine with parts of the cover broken away to expose the invention and associated mechanism;

Fig. 2 is a fragmentary detail elevation, partly in section, of the control mechanism for the multiplying unit, taken from the left side of the machine;

Fig. 3 is an elevational detail view of the base control mechanism, looking towards the right of the machine;

Fig. 4 is a fragmentary cross sectional view taken along line 4—4 of Fig. 3;

Fig. 5 is a plan view taken along line 5—5 of Fig. 4;

Fig. 6 is a fragmentary isometric view, of the invention, showing the relation that the various control links bear to each other;

Fig. 7 is a fragmentary left-hand elevational detail view of the invention showing the related position of the various links of the invention to the main shaft of the machine.

As previously mentioned, the machine of this invention comprises three mechanisms which act together, in properly timed relationship, to perform the three operations of sensing, multiplying, and punching of various factors in a perforated card.

The operation of this machine as a whole is essentially the same as the operation of the machine described in the above mentioned application S. N. 69,570.

The machine itself, differs mechanically from that of S. N. 69,570 in that there is only one motor in the present machine as compared to two motors in the other machine. Also there is added to the sensing unit of the present machine a special control mechanism which does not appear on the machine of the Dreher application.

Referring to Figs. 1 and 3 a starting button 1 is fixed on the forward end of a plunger 2 which protrudes through and is slidably mounted in a housing on the forward wall of the base frame 3. The plunger is provided with suitable limit stops and is normally held in position shown in Fig. 3 by a suitable spring (not shown). A pin 4 con-

ncts the plunger 2 to a link 5 which extends rearwardly and is connected to an arm 6 pivoted on a frame stud 7. A forwardly extending hooked member 8 is pivotally mounted on the upper end of arm 6 and is urged downwardly by a spring 9 extended from the midpoint of the arm to a rearwardly extending ear on a vertical link 10. The lower portion of the hook 8 lies in the same vertical plane as an upwardly extending toggle breaking arm 11 which, (in Fig. 3) is pivotally connected to a frame stud.

When starting button 1 is pressed hook 8, through the toggle breaking arm, effects the breaking of two toggles. Both toggles lie behind link 10 and are relatively positioned one directly behind the other (as viewed in Fig. 3). One of the toggles is pivotally connected to and cooperates with link 10 while the other is pivoted on the frame stud and cooperates with a rock arm 11. The operation and construction of these toggles is described in detail in the above cited application.

Breaking of the two toggles permits an arm 11 fixed to a transverse shaft 12, to rock clockwise under the influence of a clutch spring (not shown). Rocking of arm 11 engages a clutch to a pulley (on the right side of the machine and, therefore, not shown) thus beginning a cycle of operation of the base mechanism.

30 The vertical link 10 extends upwardly through suitable slots in the upper frame piece, 13, of the base of the machine, and is pivotally connected to the forward end of an adjustable two armed lever 14. Lever 14 is pivoted, near its midpoint, 35 on a stud 15 and is provided at its rearward end, with a lug 16 that overlies an interponent 17. Interponent 17 is in vertical alignment with lug 16 on the lever 14, and the upper end of an actuator link 18. Link 18 is connected to and operated by an arm 19, which is suitably pivoted on a frame stud 20 and is provided with a follower roller 21 cooperating with a cam 22 fixed to a main operating shaft 81.

Immediately after the base cycle has been 45 started, the broken toggle cooperating with link 10, is straightened by the action of a spring, which spring, is constantly tending to keep the toggle in a straightened position, thereby elevating vertical link 10 and rocking lever 14 to 50 place lug 16 in close proximity to the interponent 17. Thus when the link 10 is in its elevated position, a rigid connection exists between lever 14 and arm 11, consisting of the upper portion of link 10 and the straightened toggle. Therefore 55 when the high spot on cam 22 elevates link 18 the lever 14 will rock clockwise to depress link 10 and rock, therethrough, arm 11 to disengage the clutch, thereby stopping the base mechanism.

As the arm 11 is rocked the second toggle, 60 which is pivoted on the frame stud, is straightened by its spring and holds arm 11 in its rocked position until the toggles are again broken, to initiate another cycle of the base mechanism.

Also, when cam 22 has rotated through approximately 235 degrees of a revolution, the high spot thereon rocks an offset bell-crank 23 pivoted on frame stud 20. The other arm 24, of the bell-crank, is connected by a pin-in-slot connection to a control link 25. A spring 26 tensioned between the pin on the bell-crank arm and a stud on link 25 resiliently holds the two members in cooperative relation.

The upper extremity of link 25 (see Fig. 2) is connected to and rocks an arm 27 pivoted on a stud 28 on the side frame of the head mechanism.

Arm 27 is formed with a nose which overlies a bent-over ear on a latch 29 and cooperates with the latch to release a cross head bumper 30 (Fig. 1). Release of the bumper 30 initiates a multiplying cycle by starting a cross head 31 on its rearward stroke. The aforementioned application S. N. 69,570 of Elmer H. Dreher describes completely and in detail the construction and operation of the cross head 31 and also describes the various mechanisms and operations controlled thereby.

The relative timing of the various base mechanisms is such that, during the period in which the high spot on cam 22 is traveling from its starting position (as shown in Fig. 3) to a position immediately before it rocks bell-crank 23, the feed rolls will have passed a card into the sensing chamber and the sensing mechanism will have effected a key set-up corresponding to the information contained in the card. When the arm 24 is rocked, link 25 will be depressed and will release bumper 30, by engaging the bent over portion of latch 29 with arm 27 thus starting a multiplication cycle. During the remaining 125 degrees of revolution of the cam 22, the card is passed into a punching chamber and the base mechanisms are returned to normal position, after which, they are stopped when the high spot on the cam 22 effects the disengagement of the drive clutch. The multiplying unit, having been started during the base cycle, continues through its cycle after the base component has been stopped and is, finally, brought to rest when the cross head is returned to its home position.

Thus it is apparent that a complete cycle of operation of the machine consists of a cycle of the base component and a partially overlapping cycle of the multiplying unit.

As the cross head starts on its rearward stroke, it rocks a cam lever 32, (lever 201 in Fig. 49 of above mentioned application S. N. 69,570) in a clockwise direction. The lever is again returned to its normal position (as shown in Fig. 2 of this specification and Fig. 48 of S. N. 69,570) when the cross head, on its forward stroke, returns to its home position. This rocking of lever 32, with each cycle of the multiplying component, is utilized to restart the base mechanism and thereby enable the machine to operate automatically.

A lever 33 pivoted on a frame stud 34 is provided with a follower roller 35, on its downwardly extending arm, adapted to ride upon a cam face 36 on lever 32. A horizontal link 37 connects the other arm of lever 33 to the vertical arm of a bell-crank 38 pivoted on the forward part of the multiplying unit side frame. The horizontal arm of bell-crank 38 is connected to and operates a vertical link 39 which extends downwardly and terminates in a hooked end element 40. The hook 40 (Fig. 3) fits into a slot formed between a short link 41 and the horizontal arm of a bell-crank 42 pivoted on the same frame stud as one of the clutch operating toggles. The vertical arm (not shown) of bell-crank 42 has a stud mounted thereon, which engages the breaking arm of each of the two toggles lying in back of link 10, thereby affecting a break every time bell-crank 42 is rocked.

The lower end of link 39 is urged forwardly by a suitable spring (in this case, spring 43, extending between a frame stud 44 and a hook element 45 secured to link 39). Hence the leading face of hook 40, on link 39, normally bears against a pin 46, which connects link 41 to bell-crank 42, as shown in Fig. 3, unless the link 39 is held in

disabled or retracted position by other means.

Thus, when the high spot on cam 22, through its associated linkage, causes cross head latch 29 to be disabled, the cross head starts rearwardly, and in so doing, rocks lever 32 clockwise which also allows lever 33 to rock clockwise, thereby allowing link 39 to drop downwardly, due to its own weight, and engage pin 46 with the hook 40. When the cross head 31 is returned to its home position, at the end of the multiplying cycle, cam face 36 on lever 32, cams the follower 35 to rock lever 33 counter-clockwise, effecting, thereby, the elevation of link 39, to rock bell-crank 42. As before stated, rocking of bell-crank 42 causes a break in the clutch control toggles which acts to initiate a cycle in the base mechanism.

It may be seen, therefore, that the multiplying mechanism will, before coming to complete rest, initiate a new cycle in the base component of the machine, while the base mechanism will, in going through its cycle (unless otherwise prevented from so doing, as will hereinafter be described), initiate a new cycle of operation in the multiplying mechanism. Thus the machine runs continuously one mechanism acting to initiate a cycle in the other, before itself coming to rest.

As hereinbefore stated, it is often desirable to pass certain cards through the base mechanism of the machine, without initiating a cycle in the multiplying component of the machine. Under such conditions those cards which are designated as control cards and are used either for a common multiplier set-up or for clearing a set-up already in the machine, are sensed and passed through the base mechanism without that component coming to a stop at the completion of its cycle. The mechanism continues running until another card is sensed, after which (unless the second card is also a control card) the multiplying mechanism control link is tripped to initiate a cycle of that component and the base mechanism stops. This result is brought about by the mechanism shown in Fig. 6. See also (Figs. 2, 3, 4, and 5).

One of the translator interponent bars, 47, similar to 447 Fig. 58 of the above application lying between the upper pin box of the sensing unit and the translator is provided with a laterally extending lug 48. In this embodiment of the invention, the bar corresponding to the second index position of the first column in a 90 column card is used, although any other position might be suitably designated to serve the same purpose. The lug 48, underlies and cooperates with an arm 49 of a bail 50 which is pivotally mounted on a shaft 51. The forward end of bail 50 (as viewed in Fig. 6) terminates in a two armed vertical lever 52, the lower arm of which has a stud, 53, mounted thereon, in cooperative relation with a hook nosed latch lever 54, pivoted on a stud 55 in a bracket 56. A spring 57 tensioned between an upwardly extending arm of bracket 56 and the forward arm of the latch lever 54, urges the latch member 54 in a counter-clockwise direction (Fig. 7). The upper arm of lever 52 has connected thereto, by a stud 58, a link 59 which is pivoted to, and rocks a lever 60 formed on a bail 61 pivotally mounted on a shaft 62. Also, connected to lever 60, at its lower extremity, is the interponent 17 which lies between actuating link 18 and lug 16 on lever arm 14. The under side of interponent 17 has a suitably located notch 63 cut therein of sufficient size and depth to permit an unhampered upward movement of link 18 when the interponent 17 is

moved forwardly of the machine (to the right as is shown in Fig. 7).

Connected to and operated by the forward arm of bail 61 (as viewed in Figs. 6 and 7) is a shoudered link 64 which underlies a stud 65 in the multiplying control link 25. The shoulder on link 64 is of a suitable contour, such that when the link is in a normal position, the multiplying control link 25 may be depressed without any interference, but when link 64 is moved forwardly (to the right Fig. 7), by the rocking of bail 50, the shoulder of the link is interposed between stud 65 and a portion of the upper side frame 13A, (Figs. 4 and 5), arresting thereby, the downward movement of link 25.

A follower roller 66 (Figs. 3 and 6) mounted on a horizontal arm 67 of a bell-crank 68 pivotally mounted on a frame stud 69 cooperates with a cam 70 on the main shaft of the base mechanism. A suitable tension spring 71 connected to the vertical arm of bell-crank 68 urges the follower into contact with the face of the cam 70. The arm 67 has a draw link 72 connected thereto, which extends through a slot in the frame piece 13 and lies adjacent the latch lever 54. A stud 73, mounted in the upper end of draw link 72 overlies and cooperates with latch member 54.

When a card having a perforation in the control position is sensed, interponent bar 47 is raised by the sensing pin thereby rocking bail 50 counter-clockwise. Rocking of bail 50 moves link 59 rearwardly of the machine to rock bail 61. Also, latch 54 engages stud 53 to hold bail 50 in operated position. The rocking of bail 61 acts, at once, to move interponent 17 and shoudered link 64 forwardly.

Forward movement of interponent 17 causes that member to take a position where link 18 may rise into the notch 63 of the interponent. Hence when at the completion of a cycle of the base mechanism, cam 22 raises link 18, that link will simply rise into the space provided in the interponent, without raising that member and, consequently, will not rock lever arm 14. Since lever 14 is not rocked at the completion of the cycle, link 10 will not be depressed to rock arm 11 and disengage, therethrough, the clutch from the driving pulley. Therefore the base mechanism will go through another cycle.

The shoudered link 64, which is also pulled forwardly upon rocking of bail 61, interposes its shoulder portion between stud 65 on link 25 and the frame piece 13A. It may be seen, therefore, that by reason of the shoulder arresting the movement of stud 65, link 25 cannot be depressed. Therefore the pin on arm 24 will simply tension the spring 26 as it moves idly through the slot in link 25, when the high spot on cam 22 operates bell-crank 23. Consequently no cycle of the multiplying mechanism will be initiated.

Also, at the beginning of each cycle of operation of the base mechanism, the high spot on cam 70 depresses the follower arm 67, depressing, therethrough, draw link 72 sufficiently to cause the stud 73, mounted thereon, to raise latch lever 54 and thus unlatch stud 53 on lever arm 52. Thus the various bails and links, controlled thereby, are permitted to return to normal position, under influence of a spring 74 tensioned between link 64 and a stud 75 mounted in an adjustable member 76. Member 76 is a small rectangular steel plate having slots cut therein through which two bolts 77 pass, to ad-

justably, fix the member to frame piece 13A. The forward face 78 of member 76 acts as a limit stop for the shoudered link 64.

It is obvious, therefore, that when a card having a "control" hole and data punched therein, is sensed the information contained in the card will be transferred to, and set up in the multiplying component of the machine, but no multiplying cycle will be initiated. Also, since the clutch of the base mechanism is not disengaged under such conditions, the mechanism will continue running, to eject the control card and bring a new card into the sensing unit, without any interruption in card feeding.

15 While I have described what I consider to be a highly desirable embodiment of my invention, it is obvious that many changes in form could be made without departing from the spirit of my invention, and I, therefore, do not limit myself to the exact form herein shown and described, nor to anything less than the whole of my invention as hereinbefore set forth, and as hereinafter claimed.

What I claim as new, and desire to secure by Letters Patent, is:

1. In a record controlled multiplying machine having record card feeding and sensing mechanism, driving means therefor, computing mechanism acting to perform multiplication involving factors sensed by said sensing mechanism, driving means for said computing mechanism, each of said mechanisms including means normally acting to stop its associated mechanism at the end of each cycle of operation thereof, a link operated by said feeding and sensing mechanism and normally acting to initiate an operation of said computing mechanism, and means whereby said computing mechanism initiates an operation of said feeding and sensing mechanism whereby normally the machine operates continuously in a succession of alternating cycles of the two said mechanisms, the combination of a pair of elements arranged for movement with a common movable member, one of said elements cooperable with said link and the other of said elements cooperable with said means for stopping the card feeding and sensing mechanism, means for imparting movement to said member upon the sensing of a special perforation in a record card to simultaneously move said first mentioned element to a position whereby the same blocks the action of said link to prevent a cycle of said computing mechanism and the second mentioned element to a position whereby the same temporarily disables the means for stopping the card feeding and sensing mechanism so that the latter will operate through two successive cycles without an intervening cycle of the computing mechanism, and a latch for holding said movable member in said moved position.

2. In a record controlled multiplying machine having record card feeding and sensing mechanism, driving means therefor, computing mechanism acting to perform multiplication involving factors sensed by said sensing mechanism, driving means for said computing mechanism, each of said mechanisms including means normally acting to stop its associated mechanism at the end of each cycle of operation thereof, a link operated by said feeding and sensing mechanism and normally acting to initiate an operation of said computing mechanism, and means whereby said computing mechanism initiates an operation of said feeding and sensing mechanism whereby normally the machine operates contin-

uously in a succession of alternating cycles of the two said mechanisms, the combination of a pair of elements arranged for movement with a common movable member, one of said elements cooperable with said link and the other of said elements cooperable with said means for stopping the card feeding and sensing mechanism, means for imparting movement to said member upon the sensing of a special perforation in a record card to simultaneously move said first mentioned element to a position whereby the same blocks the action of said link to prevent a cycle of said computing mechanism and the sec-

ond mentioned element to a position whereby the same temporarily disables the means for stopping the card feeding and sensing mechanism so that the latter will operate through two successive cycles without an intervening cycle of the computing mechanism, and a latch capable of holding said device in said moved position and under control of said card feeding and sensing mechanism whereby same will be released during a cycle subsequent to the sensing of the special perforation.

CARL E. LENZ.
